UNITED STATES PATENT OFFICE.

WILLIAM S. GORTON, OF LONDON, ENGLAND, ASSIGNOR TO WESTERN ELECTRIC COMPANY, INCORPORATED, OF NEW YORK, N. Y., A CORPORATION OF NEW YORK.

SIGNALING SYSTEM.

Application filed August 21, 1923. Serial No. 658,514.

This invention relates to the transmission of electric currents, and aims to provide improvements in the two-way transmission of such currents, for instance in the two-way repeating of telephonic currents.

Where such repeating is desired without necessitating balancing the impedances of the lines connected to the repeater system to avoid singing of the repeater system due to local circulation of power between the repeater elements, it has heretofore been proposed to employ switching means responsive to voice currents or other transmission for conditioning the repeating means to repeat in the desired direction. However, in such systems the necessity for accomplishing the closing of a switch contact in response to the transmission in order to condition the repeater to transmit in the desired direction, tends to introduce a loss in articulation, dependent upon the time consumed in closing the contact.

In accordance with the invention a voice controlled repeater or current path is rendered operative to repeat or transmit in the desired direction, or its transmitting efficiency in such direction is increased, immediately upon the opening of a switch contact, the opening of the contact being accomplished in response to voice currents, high frequency signaling currents, or the like, and without delay due to other mechanical movement, and a great gain in articulation is thereby attained, because, as recent tests of the speed of operation of relays have shown, the time required for a relay to break, or open its contact, is far less than the time consumed in the travel of the armature to make or close a contact.

Fig. 1 of the drawing is a circuit diagram of one embodiment of the invention; and Fig. 2 is a diagram of the preferred embodiment, employing push-pull amplifiers.

Referring especially to Fig. 1, R_E and R_W are amplifiers, preferably of the well known electron tube type, for transmitting energy from line W to line E and from line E to line W , respectively, the tube R_E being coupled to line W by a transformer 1 and to line E by a transformer 2, and the tube R_W being coupled to lines E and W by transformers 4 and 6, respectively. Negative grid potentials for tubes R_E and R_W are furnished by batteries 10 and 10', respectively, or the like. Associated with tube R_E are two equal

sources of E. M. F. such as batteries 11 and 12, two equal resistances 13 and 14, and two resistances 15 and 16 which are also equal to each other. One end of each of the resistances 15 and 16 is connected to the filament of tube R_E and to the negative pole of battery 11, the positive pole of battery 12, and ground, as shown. The other ends of resistances 15 and 16 are connected to the left hand ends of resistances 13 and 14, respectively, the right hand end of resistance 13 being connected to the positive pole of battery 11 and the right hand end of resistance 14 being connected to the negative pole of battery 12. The left hand ends of resistances 13 and 14 are connected by a lead 17 which includes the armature 18 of a relay 19, the coil of relay 19 being designated 20.

Associated with tube R_W are elements 11' to 20' corresponding to elements 11 to 20 associated with tube R_E .

Connected to line W by transformer 1 is the input circuit of valve relay T_E of the kind described by Captain L. B. Turner in the London Electrician for July 4, and July 11, 1919, and in British patent to Turner, No. 130,408, accepted August 7, 1919; and the input circuit of a similar valve relay T_W is connected to line E by the transformer 4. The term "valve relay" is used to designate T_E and T_W to distinguish these elements from the amplifiers R_E and R_W , and to avoid confusing these elements with the ordinary contact relays to be referred to later. When a three-electrode space discharge tube or valve is used as an amplifier, the valve and its associated circuits are so-arranged that a primary electromotive force of small power produces a secondary, generally larger, electromotive force of larger power, the wave form of which corresponds more or less to the wave form of the primary electromotive force. The term "valve relay" on the other hand, is used to define an instrument wherein the secondary effect is produced by, but is not necessarily a reproduction of, or proportional to the primary electromotive force or current. The valve relay T_E comprises a three-electrode space discharge tube or valve V , having the usual cathode, anode and grid elements, and having an anode battery B_a , a grid battery B_g , an inductance I_a in its anode circuit, and an inductance I_g , shunted by a capacity C_g , in its grid circuit, I_a and I_g being mutually inductive. The anode I_a

circuit also includes the coil of a contact relay CR, the armature t of which is adapted to short circuit the inductance Ia . The elements V, Ba, Bg, Ia , Ig, Cg, CR, and t correspond to the similarly designated elements in the Turner patent mentioned above; and the corresponding elements of valve relay T_w are designated V', B'a, B'g, I'a, Ig, C'g, CR' and t' , respectively.

As explained in the Turner patent, the grid potential of tube V should be adjusted to the critical value just below the value necessary to set up oscillations in the circuits of the inductances Ia and Ig due to the reaction of the anode and grid circuits upon each other by mutual inductance between the respective circuits, so that when a signal impulse is impressed on the grid circuit oscillations will be started, the amplitude of the oscillations immediately rising to a large value, and being accompanied by a sudden large increase in the mean value of the anode current. At this critical value of grid potential the action of the device is very sudden, a very small rise in the grid potential being sufficient to produce a change from the stationary to the oscillatory condition. The increase in the mean anode current operates relay CR, which short circuits the inductance Ia to stop oscillations in the valve relay circuit, and thus to restore the valve relay to condition to be again operated in response to signal current; for when the valve relay has been set into oscillation, the oscillations would continue even after the signal currents which initiated them had ceased to flow, unless some relay restoring means were employed. The oscillations set up may be made of any high, low or intermediate frequency, by suitably choosing or adjusting the various reactances. The use of a high frequency is preferable since in that case the setting up of oscillations by the signal requires no appreciable time. The adjustment and operation of valve relay T_w is the same as that just described for valve relay T_E .

Normally, that is when no transmission is approaching the repeater over line W or line E, the grid potential of tube V is maintained at the critical value mentioned above by a negative potential from the grid battery Bg, the lead 17' being then at ground potential with current flowing from the positive pole of 11' through resistance 13', lead 17', armature 18', resistance 14' and battery 12' to the negative pole of battery 11' and producing voltage drops in 13' and 14' equal and opposite to the voltages of batteries 11' and 12' respectively. No current then flows through resistance 15' or resistance 16', and there is no voltage drop in either of the resistances 15' or 16'.

Similarly, the grid potential of tube V' is normally maintained at the critical value mentioned above by a negative potential from

the grid battery B'g, the lead 17 being then at ground potential with current flowing from the positive pole of battery 11 through resistance 13, lead 17, armature 18, resistance 14, and battery 12 to the negative pole of 70 battery 11 and producing voltage drops in 13 and 14 equal and opposite to the voltages of batteries 11 and 12 respectively, and there being no voltage across, or current in, either of the resistances 15 and 16. 75

Further, the tubes R_E and R_w are normally rendered inoperative to transmit by negative potentials from batteries 10 and 10', respectively.

In the operation of the system, when transmission approaches the repeater from, say line W, it enters T_E and when the energy of this transmission exceeds a certain definite amount the valve relay T_E will oscillate, thus increasing its plate current and thereby causing relay 19 to open contact 18. 80

As soon as the armature 18 leaves its back contact, battery 11 sends a current from its positive pole through resistance 13 and resistance 15, to its negative pole, and this current causes a voltage drop in resistance 15. Also, battery 12 sends a current from its positive pole through resistance 16 and resistance 14, to its negative pole. The drop in 15 renders tube R_E operative to repeat 90 transmission from line W to line E; and the drop in 16 renders valve relay T_w inoperative so that it cannot be set into oscillation by the voltage which R_E delivers to line E. This condition persists as long as energy is 100 incident upon the repeater. When energy is no longer incident upon the repeater the original or normal state of affairs is resumed. Although the relay 19 should be quick to open, it should be made slow closing, for instance, by arranging it to have a weak restoring force, as the example, by providing it with only a weak restoring spring (not shown). This will insure that the tongue t opens before contact 18 closes, so that if 110 transmission is still approaching the repeater from line W, the relay T_E will repeat its cycle of operation and so maintain contact 18 open as long as energy is coming in.

For transmission from line E to line W 115 the operation of the repeater is similar to the operation just described for transmission from W to E, the valve relay T_w rendering tube R_w operative and valve relay T_E inoperative. Contact 18' should, of course, 120 be slow closing like contact 18, for the reason pointed out in connection with contact 18.

Making the amplifiers R_E and R_w operative and inoperative, as shown in Fig. 1, by variation of the plate currents sends out 125 large impulses of energy upon the lines. The sending of these noise currents out on the lines can be obviated by making the amplifiers of the push-pull type, as shown at R'_E and R'_w in Fig. 2 which is otherwise like 130

Fig. 1. The individual portions of the input circuits of the upper and lower tubes of the push-pull amplifier R'_E are associated with the primary winding of the input transformer 1 by the upper and lower halves, respectively of the secondary winding of the input transformer, so that currents to be amplified cause potentials of opposite signs to be applied to the grids of the upper and lower tubes of the amplifier simultaneously. The individual portions of the output circuits of the upper and lower tubes of the amplifier are associated with the secondary winding of the output transformer 2 by the upper and lower halves, respectively, of the output transformer, so that an increase in the plate current of the upper tube and a decrease in the plate current of the lower tube act cumulatively upon the secondary winding. The voltage across resistance 15 is preferably applied to the common portion of the input circuits of the two tubes, as shown, and tends to make the potentials of the grids of the two tubes the same in sign at any given time. Thus, when this voltage renders the upper tube operative or inoperative it simultaneously affects the lower tube in the same way, and the consequent changes in the space currents of the tubes act differentially upon the secondary winding of the transformer 2, so that noise currents on line E due to these changes of space current are obviated. The action of the push-pull amplifier R'_E in avoiding the sending out on line W of noise currents due to rendering the tubes of that amplifier operative and inoperative, is similar to the action just explained for amplifier R'_E .

The invention is not limited to the details of the disclosure, but is capable of various and widely different embodiments within the spirit and scope of the appended claims.

The invention claimed is:

1. In a signaling system comprising a current transmission path and a circuit-controlling device therefor having movable operating parts of substantial inertia, the method of operation of said system which comprises causing said parts to so move in response to flow of signaling current in said path as to make the operation of said device substantially independent of said inertia, and increasing the transmitting efficiency of said path immediately upon the operation of said circuit-controlling device.

2. In a repeating system comprising a repeating element, a controlling switch therefor including operating elements having material inertia, the method of operating said system which comprises causing said switch to respond to signaling currents within a negligible time after the application of said currents thereto, and causing a change in the repeating power of said repeating element

substantially immediately after the operation of said switch.

3. In a two-way repeating system comprising a repeater and a controlling switch therefor including operating elements having substantial inertia, the method of operating said system which comprises producing an opening of said switch in response to signaling currents within a negligible time after the application of said currents thereto, and rendering said repeater operative to repeat in the desired direction within a negligible time after the opening of said switch.

4. In an amplifying system comprising an electron tube amplifier and a controlling switch therefor including operating parts having substantial inertia, the method of operation which comprises causing said switch to open in response to signaling currents in a negligible time after the application of said currents thereto, and rendering said amplifier operative substantially immediately after the opening of said switch.

5. In combination, a current transmission path, a circuit controlling device therefor having movable operating parts of material inertia, means for so moving said parts in response to signaling currents as to substantially eliminate the effect of said inertia on the operation of said device, and means responsive to the operation of said parts for immediately increasing the transmission efficiency of said path.

6. In a transmission system, a repeating element, a controlling switch therefor including operating parts of substantial inertia, a source of signaling currents, means for causing said switch to respond to said signaling currents in a negligible time after their application thereto, and means for increasing the repeating power of said element in a negligible time after the operation of said switch.

7. A transmission system comprising a switch, a normally inoperative electron tube amplifier having a control electrode, a source of signaling currents, means responsive to said signaling currents for opening said switch in a negligible time after the application of said signaling currents thereto, and means, operative immediately upon the opening of said switch, for applying to said control electrode an electromotive force of such character as to render said tube operative.

8. A two-way repeating system comprising a circuit, two normally inoperative electron tube amplifiers for transmitting in opposite directions respectively, in said circuit, two relays each comprising a contact, means responsive to signaling currents approaching said amplifiers in one direction over said circuit for opening said contact associated with one of said relays in a negligible time.

- after the application of the signaling currents thereto, means for rendering one of said amplifiers operative to transmit in said one direction and rendering said other relay 40
5 inoperative immediately upon the opening of said other contact, means responsive to signaling currents approaching said amplifiers in said other direction over said circuit for opening said other contact in a negligible 45
10 time after the application of said other signals thereto, and means for rendering said other amplifier operative to transmit in said other direction and rendering said other relay inoperative immediately upon the opening 50
15 of said contact.
9. A transmission system comprising a switch, a push-pull electron tube amplifier, means normally maintaining the space current of said amplifier at zero value, a source 55
20 of signaling currents, means responsive to said signaling currents for opening said switch in a negligible time after the application of said signaling currents thereto, and means, operative immediately upon the 60
25 opening of said switch, for causing space current to flow in said amplifier.
10. A transmission system comprising an amplifying device, means to impress signaling currents thereon and separate means including an oscillation generator also responsive to said signaling currents for controlling the transmitting efficiency of said device. 65
30
11. An amplifying device, means to impress signaling currents thereon and means for controlling the transmitting efficiency of said device, said means comprising an oscillator 70
35 also subjected to said signaling currents, said oscillator circuit being normally quiescent but oscillating in response to said signaling currents. 40
12. A two-way signaling system comprising a path for transmitting signaling currents in opposite directions, respectively, between two points, and means for controlling the transmitting efficiency of one of said paths, said means comprising an oscillator normally quiescent but oscillating in response to signaling current. 45
13. A two-way signaling system comprising a sending station, a unidirectional current transmitting path for transmitting signals from said station, an oppositely directed unidirectional current transmitting path for transmitting signals to said station, and means comprising an oscillator responsive to 50
55 signaling current for applying a direct current potential to one of said paths to control its transmitting efficiency.
14. A source of electromotive force, a resistance connected thereacross, a second source of electromotive force, a resistance thereacross, said sources having poles of opposite signs, respectively, connected together, and a conductor including a switch connecting points in said resistances which are at the same potentials, respectively, as the potentials of said opposite poles connected together. 60
65

In witness whereof, I hereunto subscribe my name this seventh day of August A. D., 70
1923.

WILLIAM S. GORTON.
